ENGINE GOVERNOR

Marion Mallory, Detroit, Mich.

Application March 1, 1945, Serial No. 580,450

11 Claims. (Cl. 123—103)

1

This invention relates to a governor for controlling the speed of an internal combustion engine, and more particularly to an engine speed governor which is actuated by changes in the intake passageway pressure.

It is the object of this invention to produce a governor for an internal combustion engine of the type actuated by changes in the intake passageway pressure which will effectively control the speed of the engine substantially free from surging.

Fig. 1 is an elevation partly in section showing my speed governor assembly.

Fig. 2 is a detail of the centrifugal air bleed valve.

Fig. 3 is an enlarged detail showing a modified form of the centrifugal air bleed valve.

Fig. 4 is a detail of a second modified form of centrifugal air bleed valve.

Fig. 5 is a detail of the same form of centrifugal air bleed valve as shown in Fig. 4 but provided with an orifice adjustable relative to the valve.

Fig. 6 is a front elevation of the valve housing and adjustable orifice member.

Fig. 7 is a view similar to Fig. 5 showing the orifice member adjusted further inwardly than in Fig. 5.

The parts of my engine governor assembly are referenced as follows: intake passageway 1 having inlet opening 2 and outlet to the engine 3, governor valve 4 of the butterfly type, governor valve shaft 5, tension spring 6 connected to arm 7 which is fixed on valve shaft 5, suction device 8, suction chamber 9, flexible diaphragm 10, rod 11 connecting diaphragm 10 with arm 7, orifice 12 on the atmosphere side of valve 4, conduit 13 connecting orifice 12 with suction chamber 9, orifice 14, conduit 15 connecting orifice 14 with suction chamber 9, conduit 16 connected into conduits 13 and 15 and connecting suction chamber 10 with circumferential passageway 17 and T passageway 18 in distributor shaft 19, valve housing 20 fixed on shaft 19, piston valve body 21, tension spring 22, internally threaded block 23 and adjusting screw 24 which can be turned to move block 23 to increase or decrease the tension of spring 22, by-pass groove 25 in valve body 21, valve 26, tapered metering pin 27, air bleed orifice 28 and orifice 29 in distributor housing 30 through which the interior of the housing communicates with atmosphere, valve seat 31.

Operation.—As shown in Fig. 1, the governor valve 4 is wide open and the engine has not yet attained its governed speed. As the engine

2

reaches its governed speed, valve 26 will momentarily close against valve seat 31 thereby momentarily cutting off air flow through bleed orifice 28. The taper or angle of conical valve 26 and conical valve seat 31 is sufficiently large or obtuse so that valve 26 will not stick to valve seat 31. Further, valve 26 serves to momentarily close air bleed orifice 28, but the instant that valve 26 opens the metering of the air is accomplished by metering pin 27. Thus, metering pin 27 and opening 28 are correlated in cross sectional area so that the clearance between metering pin 27 and orifice 28 will always be less than the clearance between valve 26 and seat 31 except when valve 26 is fully closed. As valve 26 momentarily closes, the velocity of the motive fluid by orifices 12 and 14 create a depression or vacuum in chamber 9 which causes diaphragm 10 to move toward the right and swing valve 4 toward closed position. As valve 4 moves toward closed position, the vacuum increases at orifice 14 and thus the vacuum in chamber 9 is increased, drawing valve 4 further closed. However, the instant that valve 26 closes, a vacuum builds up in line 16 and in housing 20 in back of or to the right of valve 26 and valve body 21. This suction acts with tension spring 22 to open valve 21 slightly upon a slight decrease in the speed of the engine due to the partial closing of valve 4.

As valve 26 opens, metering pin 27 immediately takes over the metering of the air bleed through orifice 28. Since pin 27 is tapered or conical, the further valve 26 opens the less metering pin 27 restricts flow through orifice 28 and as valve 26 moves toward closed position the more metering pin 27 restricts orifice 28. Metering pin 27, valve 26 and valve body 21 are preferably integral and in any event are fixed together so that they move back and forth as a unit. The suction or vacuum behind valve body 21 cooperates with spring 22 to open valve 26 so that the valve actually rides the vacuum or air flow through orifice 28 and air bleeds suction chamber 9 sufficiently so that valve 4 will throttle the charge in accordance with the load imposed upon the engine to maintain the speed of the engine free from any substantial surging. If the load on the engine is even appreciably increased, the speed of the engine will only decrease slightly thereby causing valve 26 and metering pin 27 to move to the right and thereby further bleed down the vacuum in chamber 9. If the load is decreased, then upon only a slight increase in the speed of the engine, valve 26 and metering pin 27 will move toward the left and decrease the air bleed

to chamber 9, thereby causing diaphragm 10 to move valve 4 toward closed position to throttle the charge sufficiently to maintain the engine at its governed speed.

It is important that the metering of the air charge should be accomplished by a metering pin such as 27 and not by valve 26. If one attempts to meter the air through a valve such as 26, then the taper on the valve has to be so acute to obtain proper metering of the air bleed that the valve will stick and cause undesirable surging of the engine speed.

In Fig. 3 I have shown a modified form of valve which accomplishes the same end as the valve shown in Fig. 2. In this form of valve the valve housing 40 is integral with the distributor shaft 19 and the reciprocating valve 41 is provided with a tapered groove 42 which communicates with passageway 18 through a passageway 43 and with atmosphere through air bleed orifice 44 in the valve housing. In this form of the invention valve 41 functions the same as valve 21, 26, 27 in the principal form of the invention. Orifice 44 is shut off when valve 41 abuts the end wall 45 of housing 40. Tapered groove or relief 42 cooperates with orifice 44 to meter the air bleed. When the valve 41 is retracted by spring 22 closest to the axis of rotation, then tapered groove 42 does not restrict the air flow through orifice 44. The further centrifugal force moves valve 41 radially outward from the axis of rotation, the more tapered groove 42 restricts air flow through orifice 44 and finally shuts the same off when valve 41 abuts the outer end 45 of the housing. Valve 41 moves toward closed position against the tension of spring 22 and the intake manifold suction applied to the rear end of the valve.

In the modified form shown in Figs. 4 to 7, the several parts of the centrifugal air bleed valve mechanism are referenced as follows: housing 50 mounted on distributor shaft 51, tension spring 52 fixed at one end to the end of the housing as at 53 and at the other end to the valve body 54 as at 55, conical valve 56 carried by valve body 54, conical valve seat 57 against which valve 56 seats, tapered orifice 58, and cylindrical metering pin 59 carried by valve 56. Preferably pin 59, valve 56 and body 54 are integral. Orifice 58, in the form shown in Figs. 5, 6 and 7, is located in orifice member 60 which has a threaded fit 61 in chamber 62 of valve housing 50. Compression spring 63 is positioned between orifice member 60 and shoulder 64 and holds orifice member 60 in its adjusted position. Member 60 is provided with spaced notches 65 which receive a spanner wrench for adjusting orifice member 60 with respect to valve 56 and pin 59.

In the form of valve shown in Figs. 4 through 7, valve 56 seats against valve seat 57 momentarily to shut off air flow through orifice 58 as the engine reaches its governed speed, but the metering of the air flow through orifice 58 is controlled entirely by cooperation of metering pin 59 and the conical or tapered orifice 58. The instant that valve 56 moves off seat 57, air flows through orifice 58, around pin 59, and the further toward the right pin 59 is moved, Fig. 4, the greater the effective size of orifice 58 and the greater the air flow. When housing 50 is rotating at a relatively slow speed, or when not rotating, spring 52 holds valve body against seat 65. The governed speed of the engine can be altered by adjusting orifice member 60. If orifice member 60 is turned inwardly or toward the right to the position shown in Fig. 7, the governed speed of the engine will be lower

than if orifice member 60 is turned outwardly or toward the left, Fig. 5. In other words, the further that orifice member 60 is adjusted inwardly of chamber 62, the lower the engine speed at which valve 56 will seat against seat 57 and shut off the air bleed to the suction device, and vice versa. Thus, by the simple expedient of adjusting orifice member 60 with respect to valve 56, I am able to change the governed speed of the engine without in any wise adjusting or changing the stress on, or tension of, spring 52.

I claim:

1. In an internal combustion engine having an intake passageway, a device for governing the speed of the engine comprising a governor valve for controlling the flow of motive fluid through said passageway, a device actuated by intake passageway suction and having an operative connection with said governor valve, a conduit connecting said device into said passageway between the governor valve and the engine, a valve housing, a conduit connecting said valve housing with the suction device, an orifice in said housing for bleeding fluid into said conduit, a centrifugally unbalanced valve in said housing responsive to changes in engine speed solely for closing said orifice as the engine exceeds its governed speed and for opening said orifice as the engine falls below its governed speed, and metering means in said housing responsive to changes in engine speed and co-acting with said fluid bleed orifice solely for metering the fluid flow through said orifice, said metering means increasingly restricting fluid flow through the fluid bleed orifice as the valve moves toward closed position and decreasingly restricting fluid bleed through said orifice as the valve moves in the opposite direction.

2. In an internal combustion engine having an intake passageway, a device for governing the speed of the engine comprising a governor valve for controlling the flow of motive fluid through said passageway, a device actuated by intake passageway suction and having an operative connection with said governor valve, a conduit connecting said device into said passageway between the governor valve and the engine, a valve housing, a conduit connecting said valve housing with the suction device, an orifice in said housing for bleeding fluid into said conduit, a centrifugally unbalanced piston in said housing responsive to changes in engine speed, a valve carried by said piston and moving therewith solely for closing said orifice as the engine exceeds its governed speed and for opening said orifice as the engine falls below its governed speed, and metering means also carried by said piston and co-acting with said fluid bleed orifice solely for metering the fluid flow through said orifice, said metering means increasingly restricting fluid flow through the fluid bleed orifice as the valve moves toward closed position and decreasingly restricting fluid bleed through said orifice as the valve moves in the opposite direction.

3. In an internal combustion engine having an intake passageway, a device for governing the speed of the engine comprising a governor valve for controlling the flow of motive fluid through said passageway, a device actuated by intake passageway suction and having an operative connection with said governor valve, a conduit connecting said device into said passageway between the governor valve and the engine, a valve housing, a conduit connecting said valve housing with the suction device, an orifice in said housing for bleeding fluid into said conduit, a valve seat at

one end of said orifice, a valve in said housing responsive to changes in engine speed for seating against said valve seat and closing said orifice when the engine exceeds its governed speed and for opening said orifice when the engine falls below its governed speed, and metering means carried by said valve and always projecting into said orifice for metering the fluid flow through said orifice, said metering means decreasing the effective size of said fluid bleed orifice as the valve moves toward closed position and increasing the effective size of said orifice as the valve moves in the opposite direction.

4. In an internal combustion engine having an intake passageway, a device for governing the speed of the engine comprising a governor valve for controlling the flow of motive fluid through said passageway, a device actuated by intake passageway suction and having an operative connection with said governor valve, a conduit connecting said device into said passageway between the governor valve and the engine, a valve housing, a conduit connecting said valve housing with the suction device, an orifice in one end of said housing for bleeding fluid into said conduit, a valve seat at the inner end of said orifice, a piston in said housing responsive to changes in engine speed, a valve carried by said piston for seating against said valve seat and serving solely for closing said orifice when the engine exceeds its governed speed and for opening said orifice when the engine falls below its governed speed, and a tapered metering pin carried by said valve and always projecting into said orifice for metering the fluid flow through said orifice, said metering pin decreasing the effective size of said fluid bleed orifice as the valve moves toward closed position and increasing the effective size of said orifice as the valve moves in the opposite direction.

5. The combination as set forth in claim 4 wherein the valve and metering pin are each frusto-conical with the taper of the metering pin more acute than that of the valve whereby the valve will not stick in the valve seat upon closing.

6. In an internal combustion engine having an intake passageway, a device for governing the speed of the engine comprising a governor valve for controlling the flow of motive fluid through said passageway, a device actuated by intake passageway suction and having an operative connection with said governor valve, a conduit connecting said device into said passageway between the governor valve and the engine, a valve housing, a conduit connecting said valve housing with the suction device, an orifice in said housing for bleeding fluid into said conduit, a centrifugally unbalanced piston in said housing responsive to changes in engine speed, a by-pass passageway about said piston whereby when the orifice is open fluid can bleed through the orifice and by the piston into the conduit connecting the valve housing with the suction device, a valve carried by said piston and moving therewith solely for closing said orifice as the engine exceeds its governed speed and for opening said orifice as the engine falls below its governed speed, and metering means also carried by said piston and co-acting with said fluid bleed orifice solely for metering the fluid flow through said orifice, said metering means increasingly restricting fluid flow through the fluid bleed orifice as the valve moves toward closed position and decreasingly restricting fluid bleed through said orifice as the valve moves in the opposite direction.

7. In an internal combustion engine having an

intake passageway, a device for governing the speed of the engine comprising a governor valve for controlling the flow of motive fluid through said passageway, a device actuated by intake passageway suction and having an operative connection with said governor valve, a conduit connecting said device into said passageway between the governor valve and the engine, a valve housing, a conduit connecting said valve housing with the suction device, an orifice in said housing for bleeding fluid into said conduit, a centrifugally unbalanced valve in said housing responsive to changes in engine speed for closing said orifice as the engine exceeds its governed speed and for opening said orifice as the engine falls below its governed speed, a tapered groove in the face of said valve, a passageway leading from adjacent the deepest end of said groove to the rear end of said valve, said tapered groove co-acting with said fluid bleed orifice as soon as the valve opens said orifice for metering the fluid flow through said orifice, said metering means increasingly restricting fluid flow through the fluid bleed orifice as the valve moves toward closed position and decreasingly restricting fluid bleed through said orifice as the valve moves in the opposite direction.

8. In an internal combustion engine having an intake passageway, a device for governing the speed of the engine comprising a governor valve for controlling the flow of motive fluid through said passageway, a device actuated by intake passageway suction and having an operative connection with said governor valve, a conduit connecting said device into said passageway between the governor valve and the engine, a valve housing, a conduit connecting said valve housing with the suction device, an adjustable orifice member in said housing having an orifice for bleeding fluid into said conduit, a centrifugally unbalanced valve in said housing responsive to changes in engine speed for closing said orifice as the engine exceeds its governed speed and for opening said orifice as the engine falls below its governed speed, and metering means in said housing responsive to changes in engine speed and co-acting with said fluid bleed orifice for metering the fluid flow through said orifice, said metering means increasingly restricting fluid flow through the fluid bleed orifice as the valve moves toward closed position and decreasingly restricting fluid bleed through said orifice as the valve moves in the opposite direction, the adjustment of the orifice member relative to said valve and metering means effecting a change in the governed speed of the engine.

9. In an internal combustion engine having an intake passageway, a device for governing the speed of the engine comprising a governor valve for controlling the flow of motive fluid through said passageway, a device actuated by intake passageway suction and having an operative connection with said governor valve, a conduit connecting said device into said passageway between the governor valve and the engine, a valve housing, a conduit connecting said valve housing with the suction device, an orifice member in said housing having a conical orifice and a conical valve seat therein, the taper of the valve seat being greater than that of the conical orifice, a centrifugally unbalanced piston in said housing responsive to changes in engine speed, a conical valve carried by said piston and moving therewith for seating against said conical valve seat to shut off flow through said orifice as the engine

exceeds its governed speed, and cylindrical metering means carried by said valve and projecting into said tapered orifice for co-acting with said tapered orifice to meter the fluid flow through said orifice, said cylindrical metering pin increasingly restricting fluid flow through said tapered orifice as the valve moves toward closed position and decreasingly restricting fluid flow through said orifice as the valve moves in the opposite direction.

10. The combination as set forth in claim 8 including resilient means opposing the closing of said valve whereby the governed speed of the engine can be changed by adjusting said orifice member without changing the stress of said resilient means.

11. A governor for an internal combustion engine having an intake passageway comprising a valve for controlling the flow of motive fluid through said passageway, a suction actuated device connected to said governor valve for imparting movement thereto, a conduit connecting said suction actuated device with the intake passageway on the engine side of said governor valve, a valve housing, a passageway leading from the 20 suction chamber of said suction device into said valve housing, an orifice member for said housing, a valve controlled in accordance with en-

gine speed for controlling said orifice and the flow of air from said orifice through said housing into said passageway, said valve tending to close said air inlet orifice as the engine reaches its governed speed whereby said suction device responds to intake passageway suction and moves the governor valve toward closed position, resilient means opposing the closing of said air bleed valve, and means for adjusting the orifice member relative to said speed controlled valve whereby the governed speed of the engine can be changed without adjusting the stress on said resilient means.
